UNITED STATES PATENT OFFICE.

ARTHUR TREVOR DAWSON AND GEORGE THOMAS BUCKHAM, OF WESTMINSTER, ENGLAND, ASSIGNORS TO VICKERS LIMITED, OF WESTMINSTER, ENGLAND, A BRITISH COMPANY.

ENDLESS-TRACK VEHICLE.

Application filed April 17, 1925. Serial No. 23,820.

To all whom it may concern:

Be it known that we, ARTHUR TREVOR DAWSON and GEORGE THOMAS BUCKHAM, both subjects of the King of Great Britain, residing at Vickers House, Broadway, Westminster, in the county of London, England, have invented certain new and useful Improvements in or Relating to Endless-Track Vehicles, on which application No. 8,252 for Letters Patent was filed in Great Britain April 1, 1924, and of which the following is a specification.

This invention relates to endless track vehicles and has for its object to improve the springing of the rollers running on the track.

According to the invention the axle of one roller and the axle of the next roller in the longitudinal direction of the track are connected to the vehicle frame by means of levers the inner ends of which are pivoted to part of the vehicle frame and the outer ends of which have interposed between them a spring which is energized by movement of one or the other (or both) of the levers when the rollers pass over an obstruction. The said levers are preferably of cranked form with the portions at the angle pivoted upon the roller axles and with the ends of the horizontal limbs pivoted on part of the vehicle frame, whilst the upper ends of the vertical limbs of the cranked levers co-operate with one or more springs.

In order that the said invention may be clearly understood and readily carried into effect the same will now be described more fully with reference to the accompanying drawings, in which:—

Figure 1 is a side elevation showing part of an endless track vehicle provided with interconnected rollers in accordance with the invention, the parts being illustrated in the position they occupy when the vehicle is travelling over even ground.

Figure 2 is a section taken approximately on the line 2, 2 of Figure 1, and

Figure 3 is a view similar to Figure 1 showing the parts in the position they occupy when one of the rollers passes over an obstruction.

A is the vehicle frame, B is the endless track and C, C¹ are some of the rollers running on the track. D is one of the cranked levers the horizontal limb of which is pivoted at A¹ to part of the vehicle frame and

D¹ is the other cranked lever the horizontal limb of which is also pivoted at A¹. In the construction shown the rollers are arranged in transversely connected pairs and the cranks are duplicated, that is to say cranked levers D, D¹ are pivoted at d and d¹ on the ends of the axles of each pair of rollers. Instead of the said pairs of rollers, single rollers may, in certain circumstances, be used.

The vertical limbs of the cranked levers are pivoted at d^x, d^{1x} to cylinders E, E¹ which are slidably disposed within an outer cylinder F having at its centre part an internal flange or partition F¹ serving as an abutment for the inner ends of two separate helical compression springs e, e¹ the outer ends of which bear against the closed ends of the inner cylinders E, E¹. The said outer cylinder is not attached to any fixed part so that the two springs separated by the internal flange or partition F¹ act as a single spring. The upper parts of the vertical limbs of the cranked levers have rubber pads D^x, D^{1x} which come against stops a, a¹ on the vehicle frame to limit the movement of each cranked lever when the roller passes over an obstruction as shown in Figure 3.

It will be understood that all the rollers that come into virtual contact with the ground are arranged to be sprung in the manner above described.

What we claim and desire to secure by Letters Patent of the United States is:—

1. In an endless track vehicle, the combination with the endless track, of a plurality of longitudinally spaced rollers running on said track, a plurality of levers, means for pivoting said rollers to said levers at points between the ends of the latter, means for pivoting one end of each lever to the vehicle frame and resilient means acting on the other end of each lever to oppose the upward movements of the levers about their pivoted ends.

2. In an endless track vehicle, the combination with the endless track, of a plurality of longitudinally spaced rollers running on said track, a plurality of cranked levers with substantially horizontal limbs and substantially vertical limbs, means for pivoting said rollers to said levers at the portions at the angles of the cranks, means for pivoting the ends of the horizontal limbs to the vehicle

- frame, and resilient means acting on the vertical limbs to oppose the upward movements of said levers about the pivots of their horizontal limbs.
5. 3. In an endless track vehicle, the combination with the endless track, of a plurality of longitudinally spaced rollers running on said track, a plurality of levers, means for pivoting said rollers to said levers at points between the ends of the latter, means for pivoting the contiguous ends of adjacent levers to the frame and resilient means acting on the opposite ends of said levers to oppose the upward movements of the levers about their pivoted ends.
10. 4. In an endless track vehicle, the combination with the endless track, of a plurality of longitudinally spaced rollers running on said track, a plurality of levers, means for pivoting said rollers to said levers at points between the ends of the latter, means for pivoting the contiguous ends of adjacent levers to each other and to the frame and a spring interposed between the opposite ends of each pair of vertical limbs of the levers to oppose the upward movements of said levers about the pivots of their horizontal limbs.
15. 5. In an endless track vehicle, the combination with the endless track, of a plurality of longitudinally spaced rollers running on said track, a plurality of cranked levers with substantially horizontal limbs and substantially vertical limbs and arranged in pairs with the horizontal limbs directed to-wards each other, means for pivoting said rollers to said levers at the portions at the angles of the cranks, means for pivoting the ends of said horizontal limbs to each other and to the vehicle frame and a spring interposed between the ends of each pair of vertical limbs to oppose the upward movements of said levers about the pivots of their horizontal limbs.
20. 6. In an endless track vehicle, the combination with the elements claimed in claim 2, of resilient cushioning devices which at the termination of the upward movements of the cranked levers are compressed between the outer ends of the vertical arms of the said levers and parts of the vehicle frame by direct thrusts passing approximately through the axes of the rollers so that the said levers are not subjected to bending stresses when the said devices are in operation.
25. 7. In an endless track vehicle, the combination with the elements claimed in claim 2, of a resilient pad which is carried by the outer end of the vertical arm of each of the cranked levers and which, at the termination of the upward movement of each lever comes against part of the vehicle frame to compress said pad by a direct thrust passing approximately through the axis of the roller carried by this lever so that the latter is not subjected to bending stresses when said pad is being compressed.

ARTHUR TREVOR DAWSON,
GEORGE THOMAS BUCKHAM.
